UNITED STATES PATENT OFFICE.

KENNETH M. MURCHISON, OF NEW YORK, N. Y.

DESIGN FOR A KITCHENETTE.

• 54,446.

Specification for Design.

Patented Feb. 10, 1920.

Application filed September 12, 1919. Serial No. 323,406. Term of patent 14 years.

To all whom it may concern:

Be it known that I, KENNETH M. MURCHISON, a citizen of the United States, and a resident of the borough of Manhattan, city of New York, county of New York, and State of New York, have invented a new, original, and ornamental Design for a Kitchenette, of which the following is a specification, reference being had to the accompanying drawing, forming part thereof.

The figure is a perspective view of a kitchenette showing my new design.

I claim:

The ornamental design for a kitchenette, as shown.

KENNETH M. MURCHISON.
